(57) **CLAIM**

The ornamental design for a probe for a portable coordinate measurement machine, as shown.

DESCRIPTION

FIG. 1 is a front perspective view of our new probe for a portable coordinate measurement machine;

FIG. 2 is a front view thereof;

FIG. 3 is a rear view thereof;

FIG. 4 is a right side view thereof with the left side view being a mirror image thereof;

FIG. 5 is a top view thereof;

FIG. 6 is a bottom view thereof;

FIG. 7 is a front perspective view of a second embodiment of our new probe for a portable coordinate measurement machine;

FIG. 8 is a front view thereof;

FIG. 9 is a rear view thereof;

FIG. 10 is a right side view thereof with the left side view being a mirror image thereof;

FIG. 11 is a top view thereof; and,
